UNITED STATES PATENT OFFICE.

SELDEN SCRANTON DAVIS, OF SOUTH PASADENA, CALIFORNIA.

VALVE LIFTER.

Application filed March 29, 1923. Serial No. 628,600.

To all whom it may concern:

Be it known that I, SELDEN SCRANTON DAVIS, a citizen of the United States, and a resident of South Pasadena, county of 5 Los Angeles, and State of California, have invented a new and useful Valve Lifter, of which the following is a specification.

The present invention relates to improvements in valve lifting devices and is particularly designed to be used in connection 10 with the valves of the engine of a motor vehicle. These valves are ordinarily arranged in such a manner that a plurality of the same are aligned with one another and are 15 raised successively by means of a cam shaft disposed underneath the same. To seat each valve a spring is commonly used which bears on a pin extending through the valve stem and in most types of automobiles 20 presses the valve downwardly. When it is desired to remove a valve for cleaning purposes it becomes necessary to remove the pin previously referred to, which allows the valve and the valve stem to be withdrawn 25 through the spring. Even if it is desired to grind the valve without removing the same, it is necessary to remove this pin because the pressure of the spring, which usually is rather strong, interferes 30 with the proper grinding operation. The removal of this pin, as well as the insertion of the same, after completing the operation is very difficult, due to the fact that little space is at the disposal of the operator and 35 a number of devices have, therefore, been designed to facilitate this operation. In the present invention it is proposed to disclose a tool for this purpose which is extremely simple in construction and inexpensive, and 40 which for the larger part utilizes means at the disposal of the operator by the inherent construction of the engine. The principal advantages of my device will appear as the specification proceeds.

45 The preferred form of my invention is illustrated in the accompanying drawing in which Figure 1 shows a perspective view of my tool, Figure 2 a vertical longitudinal section through a common type of a motor vehicle engine, with those portions not of immediate interest being omitted, Figures 3 and 4 detail views showing means for temporarily raising the valves, Figure 5 a top plan view of the illustration shown in 50 Figure 4, Figures 6 and 7 diagrammatic

views further illustrating the operation of my device, and Figure 8 a detail view showing the exact position of the pin relative to the tool shown in Figure 1. While I have shown only the preferred form of the invention, it should be understood that various changes or modifications may be made within the scope of the claims hereto attached without departing from the spirit of the invention.

Of the engine (1) only those parts are shown which are of immediate interest for the purpose of disclosing the operation of my invention. The engine block (2) is shown as being provided with eight valves 70 (3) to (10) respectively, some of which are intake valves and other exhaust valves. The valves which normally rest on the seats (11) communicating with the interior of the cylinders not shown in the drawing are provided with downwardly extending stems (12) adapted to be successively raised by means of push rods (13) operated by a cam shaft (14) which receives rotary motion from the crank shaft of the engine in a 75 manner not shown in the drawing. The cams (16) on the cam shaft are arranged to raise the valves successively in accordance with the requirements of the particular engine for which the valve arrangement is 80 made. The push rods (13) are usually made of larger circumference than the valve stems (12) or are provided at their top ends with suitable collars (15) of larger cross sectional area than the valve stems. The 85 latter construction is selected in this drawing for the purpose of illustrating the invention. The push rods are usually guided in bosses (17). While the successive raising of the valves is thus accomplished by means 90 of the cam shaft (14), the seating of the valve is brought about by means of springs (18) bearing on the lower face of the top member of the engine block (2) and on a pin (19) extending through the valve stem, a washer (21) being ordinarily interposed between the pin (19) and the spring for the purpose of furnishing a better seat for the latter.

No novelty is claimed for the device thus far described, which merely illustrates an arrangement commonly found in the present motor vehicles. The principal part of my engine is the plate (22) illustrated in Figure 1 and certain wedge members (25) used 105

temporarily for holding the valves in a raised position. The plate (22) may be of any suitable form and of any suitable material, the preferred form being shown in Figure 1 in which the plate is provided with a central perforation (23), and prongs (24) extending from either end so as to form recesses (26). The member (25) is preferably made wedge-shaped as shown in Figures 3 and 4, and divided into two prongs (28) forming a recess (29) adapted to receive the valve stem when the member (25) is forced into place.

The operation of my invention may be described as follows: For the purposes of this description we shall confine ourselves to the first three valves (3), (4) and (5). The operation is begun by revolving the cam shaft (14) by means of the crank handle ordinarily provided with motor vehicles whereby the valves (3), (4) and (5) are successively raised. Each valve, as soon as the same has reached its uppermost position, is held in that position by the introduction of the member (25) which is forced between the valve and the valve seat as far as can conveniently be done without the use of tools. After the valves (3), (4) and (5) have thus been raised and secured in their raised positions, further pressure is brought to bear by any suitable means such as a pry or whatever else may be at the disposal of the operator for raising the valves still higher when the members can be further inserted to retain the valves in such elevated positions. It will be understood that at this time all three valves occupy a position higher than they ever do occupy if actuated by the cam shaft only so that even if the cam shaft raises one or all of the push rods to their uppermost position they will still remain out of contact with the valve stems. The next step is to rotate the cam shaft sufficiently far that the push rod of the middle valve (4) is raised to its uppermost position. Then the plate (22) is placed on top of the push rod, which it will be understood is sufficiently lower than all three valve stems to allow of the free introduction of the plate in such a manner that the hole (23) which is smaller than the top of the push rod but larger than the valve stem, and the two recesses (26) at the end of the plate may be brought directly underneath the three valve stems of the valves (3), (4) and (5). If sufficient clearance is left between the top of the plate (22) and the bottom of the pin (19) of the valve (4) to allow of the introduction of washers underneath the plate (22), washers are introduced until the plate (22) is raised sufficiently high to reach the bottom of the pin (19). Since presumably all three valves have been raised to about the same height, the plate will simultaneously be raised sufficiently high to be substantially on a level

with the pins (19) of the two valves (3) and (5). The plate is now firmly supported on the cam (16) of the valve (4) and the wedge (25) holding the valve (4) in the uppermost position may now be removed. This removal will have no effect whatever on the valve (4). Simultaneously the wedges from the valves (3) and (5) may be removed.

Now it will be noted that the recesses (26) between the prongs (24) are larger than the hole (23) and while the hole (23) prevents the pin (19) from dropping through the same, the recesses (26) engaging the stems of the valves (3) and (5) are large enough to allow the pins to drop therethrough, while stopping the washers (21), if such are provided or the spring (18) if no washers are provided. It will thus be seen that the valves (3) and (5) are allowed to drop to their respective seats while the two springs (18) associated with these valves are held in a compressed condition by the plate (22). The removal of the pin (19) if desired for the purpose of withdrawing the valves (3) and (5) is now an easy matter, and the operation of grinding the valves may be carried out without any difficulty.

Neither springs nor washer need be removed for the operation and after the operation has been performed the valves need only be returned to their seats, whereupon the pins may be reinserted and the plate removed. To remove the plate it is preferable, of course, to first take off the pressure of the springs by re-introducing the wedges (25).

I claim:

1. In combination, a plurality of valves disposed in operative proximity having stems extending therefrom, spring means bearing on the stems for seating the valves, individual elements adapted to successively raise the valves by compressing the springs, and means adapted to be supported by one of said elements made to hold the springs of adjacent valves in a compressed condition so as to render the same inoperative.

2. In combination, a plurality of valves disposed in operative proximity having stems extending therefrom, spring means bearing on the stems for seating the valves, individual elements adapted to successively raise the valves by compressing the springs, and a plate adapted to be supported by one of said elements formed to hold the springs of adjacent valves in a compressed condition so as to render the same inoperative.

3. In combination, a plurality of valves disposed in operative proximity having stems extending therefrom, spring means bearing on the stems for seating the valves, individual elements adapted to successively raise the valves by compressing the springs, and a plate adapted to be supported by one of said elements having prongs thereon

adapted to engage the springs of adjacent valves for compressing the same whereby they are rendered inoperative.

4. The method of holding valve springs of the character described compressed for the purposes described, which consists in raising the valves successively by valve raising elements whereby the springs are compressed successively, in introducing temporary means for holding each valve in its raised position when the valve raising elements become inoperative, and in inserting a common member underneath the compressed springs and holding the same in a raised position by returning one of said elements to a spring compressing position whereby the remaining springs are held compressed when the temporary holding means are removed.

20 5. In a valve lifter, a plate having a cen-

tral opening adapted to slidably receive a valve stem but to prevent the passage of a spring retaining pin therethrough, and forked ends on the plate including prongs spaced apart to allow the passage of valve stems and their pins therethrough to engage the valve springs.

6. In combination, a plurality of valves disposed in operative proximity having stems extending therefrom, spring means bearing on the stems for seating the valves, individual slotted wedge elements adapted to successively raise the valves by compressing the springs, and a plate adapted to be supported by one of said elements formed to hold the springs of adjacent valves in a compressed condition so as to render the same inoperative.

SELDEN SCRANTON DAVIS.
